DEWAXING HYDROCARBON OIL

Robert E. Manley, Port Arthur, Tex., assignor to
The Texas Company, New York, N. Y., a cor-
poration of Delaware

Application July 25, 1931, Serial No. 553,084

4 Claims. (Cl. 196—19)

This invention relates to dewaxing hydrocarbon oil, and more particularly to an improved process of removing paraffin wax from wax-bearing petroleum oil for the production of low pour 5 test lubricating oil.

The invention broadly contemplates a process of dewaxing hydrocarbon oil wherein the oil is mixed with a liquid which is miscible therewith, suitable as a wax precipitating medium and having properties which adapt it for use as a refrigerant and cooling the resulting mixture to effect precipitation of the wax constituents by refrigeratively evaporating the diluent liquid from the filtered dewaxed liquid mixture while in indirect 10 thermal contact with the fresh wax-bearing oil mixture.

My invention contemplates diluting wax-bearing oil with a light hydrocarbon liquid composed substantially of propane and butane and in suitable proportion with the oil to produce a solution 20 from which the wax constituents may be readily precipitated upon cooling. The liquid mixture is introduced to suitable chilling means wherein it undergoes cooling to precipitate the wax constituents, following which the cooled mixture is 25 filtered to remove the precipitated wax from the dilute oil in the form of a slack wax cake.

The cooled dewaxed liquid mixture is then conducted into chilling means in indirect thermal 30 contact with the fresh dilute wax-bearing oil flowing therethrough and the diluent liquid is evaporated from the dewaxed mixture with refrigerative effect, thereby moving the diluent liquid and simultaneously cooling the fresh wax-bearing oil. If desired, and in order to further precipitate the wax constituents to the desired degree, the mixture may be further cooled by 35 passing it through additional chilling means wherein a portion of the liquid propane and butane by itself may be vaporized as a refrigerant while out of direct thermal contact with the mixture.

The remaining diluent liquid retained in the dewaxed oil mixture which has been subjected to evaporation as well as that retained in the slack wax cake, is recovered for use in treating further oil by separately subjecting the dewaxed oil mixture and slack wax to warming or heating.

In the prior art methods of dewaxing oil, the 50 oil is diluted with petroleum naphtha, or with some other miscible liquid having substantially little solvent action upon the solid wax constituents, and the resulting mixture chilled by passing it in indirect heat exchange relationship with a 55 refrigerating medium, such as brine, following

which the chilled mixture is subjected to filtration to remove the precipitated wax constituents. This type of operation necessitates the employment of virtually two distinct systems; namely, one devoted to the actual removal of the wax 5 constituents from the dilute oil; and the other devoted to supplying brine at a low temperature for use in connection with the dewaxing operation. Dewaxing systems required for this method of operation are necessarily extensive and 10 complicated, and considerable cash outlay is required to provide the necessary apparatus and equipment.

The object of my invention, therefore, is to provide a single unitary dewaxing system where- 15 in I employ a liquid material combining the properties of a wax precipitating medium with those of a refrigerating medium, thereby avoiding the necessity of employing brine as a cooling medium, and, at the same time, effecting better heat econ- 20 omy as well as greatly simplifying the entire operation.

In order to more fully disclose the invention, reference will now be made to the accompanying 25 flow diagram illustrating diagrammatically an arrangement of flow adapted to carry out my invention.

Wax-bearing oil, from a source not shown, is delivered by a pump 1 to a dilution tank 2 wherein it is mixed with a diluent liquid received 30 from a source to be described later. The dilution tank 2 is adapted to withstand pressure so as to permit maintaining the diluent and refrigerating material under sufficient pressure to prevent volatilization. From the tank 2 the dilute 35 mixture is delivered to a chilling or cooling means 3 wherein it is cooled as a result of indirect thermal contact with the evaporating dewaxed mixture, as will shortly be described in more detail.

If necessary, the mixture may be conducted 40 from the cooler 3, through an additional or secondary cooling means 4, preferably of the type into which the refrigerant material may be directly expanded, out of contact with the liquid mixture undergoing cooling, in order to produce 45 the necessary refrigerative effect. After being subjected to whatever further cooling may be desired, the dilute mixture is introduced to a tank 5, still maintained under pressure wherein it may be mixed if desired with filter-aid material which 50 may be introduced to the tank in the form of a slurry from a tank 5a.

The cooled liquid mixture containing precipitated wax is then introduced from the tank 5 to a filter press 6, advantageously of the rotating leaf 55

type, wherein the mixture is subjected to filtration under pressures of the order of 75 to 100 pounds to remove the precipitated wax and solid filter-aid material in the form of a slack wax filter cake.

5 The filtrate is conducted to a storage tank 7 from which it is delivered by a pump 8 through a pipe 9 having an expansion or control valve 10 to the evaporator side of the cooler 3. The pressure within the evaporator chamber of the cooler 3 10 surrounding the interior coils through which the fresh dilute mixture is flowing is sufficiently low to permit expansion of the dewaxed mixture entering through the valve 10, thereby resulting in the evaporation of the light diluent hydrocarbon from the mixture under such conditions that the heat necessary for vaporization is absorbed from the relatively warmer and fresh mixture flowing through the coils within the cooler 3. The diluent liquid vaporizing from the dewaxed mixture may be withdrawn from the evaporator chamber through a valve 11 by means of which, in conjunction with the valve 10, the pressure within the evaporator chamber and, therefore, the extent of vaporization therewithin may be regulated. This vaporized material is conducted through a line 12 to a compressing means 13, wherein it is converted into a liquid condition and then delivered through a cooler 14 to a pressure storage tank 15. A subatmospheric pressure 20 may be maintained within the evaporator chamber by applying vacuum thereto with the compressor 13.

30 The dewaxed mixture from which substantially all or only a portion of the diluent liquid may be evaporated is withdrawn from the evaporator chamber of the cooler 3 by a pump 16, and delivered to a stripping still 17 wherein it is subjected to heating or warming in order to vaporize the remaining retained diluent liquid. This stripping 35 is preferably carried out under pressure so that the evolved vapors will be completely condensed upon cooling in a condenser 18; otherwise recompres- 40 sion of the cooled vapors is necessary. The condensed diluent material is then conducted to the pressure storage tank 15 already referred to. The stripped dewaxed oil may be collected in a storage tank 19 for further disposition as may be desired.

45 The slack wax filter cake resulting from the filtering operation is delivered by a pump or other suitable displacing means 20 to a stripping still 21 wherein it is subjected to warming or heating to drive off the retained diluent liquid hydrocarbon material in substantially the same manner de- 50 scribed in connection with the stripping of the de- 55 waxed oil mixture. The vaporized material is conducted to a cooler and condenser 22 and the condensate from there is delivered to the pressure storage tank 15, while the stripped slack wax 60 may be withdrawn from the still to a tank 23.

65 The diluent liquid may be delivered as desired from the tank 15 by a pump 24 through a pipe 25 and valve 26 to the dilution tank 2 for use in mixing with fresh wax-bearing oil as previously de- 70 scribed. A suitable portion of the liquid may also be delivered through a pipe 27 and valve 28 to the cooler 4 for direct expansion therein on the evaporative or refrigerant side in order to effect the desired amount of additional cooling of dilute 75 wax-bearing mixture. The resulting vapor is withdrawn through a valve 29 into the pipe 12 previously referred to and leading to the compressor 13 by which means it is converted again to the liquid form for further use either as a diluent or as a refrigerant.

In practicing the invention, the wax-bearing lubricating oil stock comprising, for example, either a distillate or residual cylinder stock, or a mixture of distillate and residual petroleum fractions, is delivered to the tank 2 maintained under a pressure of around 150 pounds and mixed therein with approximately 70% of light hydrocarbon liquid composed substantially of propane and butane. The pressure to be maintained on the tank, as well as on the rest of the system, will 10 depend, of course, upon the proportion of propane in the diluent.

15 The resulting mixture at a temperature of around 90° F. is conducted through the coils of the cooler 3 wherein, due to the indirect thermal contact with the evaporating dewaxed mixture in contact with the exterior surfaces of the coils, it may be cooled to a temperature of around 40° F. or lower. The cooled mixture is then passed through chilling means 4 wherein it may be fur- 20 ther cooled to a temperature of -25° F. The chilled mixture is then delivered to the pressure filter 6 wherein it is filtered under a pressure of around 100 pounds to remove the precipitated wax in the form of a filter cake.

25 The resulting filter cake may be subjected to washing with fresh diluent liquid followed, if desired, by blowing with an inert gas in order to displace the greater portion of retained oil otherwise adhering to the cake.

30 The filtrate, consisting of dewaxed oil and diluent liquid at a temperature of around -20° F., is collected in the tank 7 maintained under pressure to avoid vaporization of the diluent material, and from there delivered to the interior of the evaporator chamber of the cooler 3 which is maintained under a pressure of around atmospheric. The vaporized material is removed from the evaporator chamber, compressed, cooled and delivered to the liquid storage tank 15. The remaining 35 mixture of unvaporized diluent and dewaxed lubricating oil is continuously withdrawn from the evaporator chamber and introduced to the stripping still 17 wherein it may be heated to a temperature ranging from 200 to 300° F. under a 40 pressure of around 160 pounds, thereby vaporizing the retained propane and butane. The vaporized material is conducted under pressure to the condenser 18 and delivered from there in the form of a liquid to the pressure storage tank 45 15 for further use. The diluent free lubricating oil having a pour test of 0° F. or lower may be withdrawn from the stripping still for further treatment as may be desired.

50 The slack wax filter cake, which may contain a substantial quantity of retained diluent liquid, is subjected to heating under conditions of pressure and temperature substantially similar to those employed in stripping the filtrate or de- 55 waxed oil in order to remove the retained light 60 material which may also be condensed under pressure and delivered in liquid form to the pressure storage tank 15.

65 While certain operating conditions have been described in the foregoing example, it is contemplated that these conditions, particularly as regards temperature and pressure, may be varied to suit different requirements. Also while the use of propane and butane has been described, other light hydrocarbons, such as propylene, butylene 70 and the like, having refrigerant properties as well as being suitable as wax precipitating media, may also be employed.

75 Obviously many modifications and variations of the invention, as hereinbefore set forth, may

be made without departing from the spirit and scope thereof, and therefore only such limitations should be imposed as are indicated in the appended claims.

5. I claim:

1. The process of dewaxing mineral lubricating oil comprising mixing wax-bearing oil with a volatile petroleum fraction of the character of propane and butane, chilling the mixture to a temperature of the order of 0° F. and below to solidify the wax, introducing the cold dilute mixture while under superatmospheric pressure to pressure filtering means, forming therein a filter cake of solid wax, continuously removing from the filter means a stream of dewaxed filtrate, and imposing sufficient pressure upon said filtrate stream during removal from the filtering means to prevent substantial vaporization of the diluent from the oil during filtration.
10. 2. The process of dewaxing mineral lubricating oil comprising mixing wax-bearing oil with a diluent comprising propane, chilling the mixture to a temperature of the order of 0° F. and below to solidify the wax, introducing the cold dilute mixture while under superatmospheric pressure to pressure filtering means, forming therein a filter cake of solid wax, continuously removing from the filter means a stream of dewaxed filtrate, and imposing sufficient pressure upon said
15. 30. filtrate stream during removal from the filtering means to prevent substantial vaporization of the diluent from the oil during filtration.

3. The process of dewaxing mineral lubricating oil comprising mixing wax-bearing oil with a liquefied hydrocarbon diluent having a vapor pressure corresponding substantially to that of propane and butane, chilling the mixture to a temperature of the order of 0° F. and below to solidify the wax, introducing the cold dilute mixture while under superatmospheric pressure to pressure filtering means, forming therein a filter cake of solid wax, continuously removing from the filter means a stream of dewaxed filtrate, and imposing sufficient pressure upon said filtrate stream during removal from the filtering means to prevent substantial vaporization of the diluent from the oil during filtration.

4. The process of dewaxing mineral lubricating oil comprising mixing wax-bearing oil with a liquefied normally gaseous diluent, chilling the mixture to a temperature of the order of 0° F. and below to solidify the wax, introducing the cold dilute mixture while under superatmospheric pressure to pressure filtering means, forming therein a filter cake of solid wax, continuously removing from the filter means a stream of dewaxed filtrate, and imposing sufficient pressure upon said filtrate stream during removal from the filtering means to prevent substantial vaporization of the diluent from the oil during filtration.

ROBERT E. MANLEY.
